UNITED STATES PATENT OFFICE.

WILLIAM HENRY ELKINS, OF BOSTON, MASSACHUSETTS.

REGULATOR FOR DYNAMOS.

SPECIFICATION forming part of Letters Patent No. 430,634, dated June 24, 1890.

Application filed June 10, 1889. Serial No. 313,800. (No model.)

To all whom it may concern:

Be it known that I, WILLIAM HENRY ELKINS, of Boston, in the county of Suffolk and State of Massachusetts, have invented a new 5 and useful Regulator for Dynamos and the Like, of which the following is a specification, reference being had to the accompanying drawings, making a part hereof, in which—

Figure 1 is a diagram illustrating my regulator at full load; Fig. 2, at half load, and Fig. 3 at minimum load. Figs. 4, 5, and 6 are sectional views on the lines 4 4, 5 5, and 6 6, and illustrate the construction of one of the rheostats.

15 My invention relates to connecting two armatures—for example, a single-ball dynamo which has two armatures or two single armature dynamos—so that the current can be regulated without undue haste, in accordance 20 with the load; and it consists in the combination of two or more armatures by means of conductors and resistances, substantially as below described.

In the drawings, A A' represent two armatures, B B' the brushes of armature A, and B² B³ the brushes of armature A'. The brushes B B², which are of like sign, are connected by the conductors b, b', and b², and there is a variable resistance R, forming part of the 30 conductors b b', and a second variable resistance R', which forms part of the conductors b' b², but whose main function is to connect or disconnect armature A and work-circuit F F L L. The brushes B² and B'— 35 that is, the positive brush of A' and the negative brush of A—are connected by the conductors b³ b⁴ and variable resistance R², forming a part of them. The two negative brushes B' B³ are connected through the work-circuit 40 F F L L and by conductor b⁵ through variable resistance R'. The brushes B B² are also connected by conductors b³ b⁶ through resistance R². When under full load, the resistance R² is adjusted, as shown in Fig. 1, thereby 45 causing conductors b³ b⁴ to form a single conductor of low resistance between the positive brush of A' and the negative brush of A, and the resistance R is adjusted to cause a high resistance in the conductors b b', of which R 50 forms a part, while the resistance R' is adjusted to form a low resistance between the conductors b² and the work-circuit F F L L,

as shown in Fig. 1. In this condition of the rheostats R R' R² the armatures are in series, the current being from brush B³ through conductors b³ R² b⁴ to brush B', and from brush B of armature A through conductor b³ R' F F L L to brush B³, the electro-motive force being then the maximum. If now, say, half the lights be put out, and assuming the lights 60 or other load to be in series, the resistance R² is adjusted so as to give a high resistance to the conductors b³ b⁴, of which R² forms a part, and the resistance R' is also adjusted to give a high resistance between all the conductors 65 of which it forms a part, while the resistance R is adjusted to make the resistance of conductors b b' small; hence armature A is practically an open circuit, for the resistances R' and R² are so great when adjusted, 70 as in Fig. 2, that no appreciable current can pass through conductors b² b⁵, which join its brushes B B' through resistance R', nor can any appreciable current pass through conductors b⁶ b⁴, which also join brushes B B' 75 through resistance R²; hence the work-circuit F F L L is fed by armature A', the current being from brush B² through conductors b b' and work-circuit F F L L to brush B³. When all the lamps are out or under minimum 80 load, the resistances R' R² are regulated so as to make the resistance slight between conductor b⁵ and the work-circuit F F L L, and also to make the resistance slight between conductors b⁶ and b³, and the resistance R is 85 adjusted to make a high resistance between the conductors b b'; hence the current generated by armature A tends to flow through conductors b⁶ b³ and in a reverse direction through brush B², armature A', brush B³, 90 work-circuit L L F F, conductor b⁵ to brush B' of armature A, and the current generated by armature A' cannot flow through conductors b and b' because of the high resistance of R, and cannot flow through conductors b³ 95 b⁴ because of the high resistance of R², nor through conductors b³ b⁶ b², because of the high resistance of R'—that is to say, each armature is neutralized by the other, as will be clear from Fig. 3, when the resistances 100 R R' R² are adjusted as indicated in that figure.

While I have shown the resistances R R' R² at both extremes and at their mesne, it

will yet be obvious that their adjustment will be intermediate between that shown in Fig. 1 and that shown in Fig. 2 when the load is between full load and half load, and between 5 that shown in Fig. 2 and that shown in Fig. 3 when the load is between half load and minimum load. I have not shown any means for adjusting the rheostats R R' R^2 , as those skilled in the art will fully understand all 10 that relates to this resistance without further description. The details of construction of rheostats R R' R^2 will be plain, also, from the drawings without further description, and they may of course be of any suitable 15 construction. As shown in the diagrams, they indicate two electrodes in a vessel of water in R , and then electrodes in a vessel of water in R' and R^2 .

While I have described my regulator as applied to keeping the current constant, it will be 20 clear that it is equally applicable to keeping

the pressure or difference of potential constant.

What I claim is—

In combination, two armatures, their 25 brushes, the main circuit, conductors, of which a rheostat forms a part, connecting the unlike brushes of the two armatures, conductors, of which a rheostat forms a part, connecting the like brushes of the armatures, conductors, of 30 which a rheostat forms a part, connecting one brush of one of the armatures with the main circuit, and conductors, of which a rheostat forms a part, connecting each brush of the other armature with the main circuit, the armatures, their brushes, the main circuit, the conductors, and the rheostats being arranged and operating substantially as described.

WILLIAM HENRY ELKINS.
